UNITED STATES PATENT OFFICE

CHARLES F. REYNOLDS, OF CLEVELAND, OHIO, ASSIGNOR TO THE EBERHARD MANUFACTURING COMPANY, OF CLEVELAND, OHIO, A CORPORATION OF OHIO

BUCKLE

Application filed May 13, 1930. Serial No. 451,888.

This invention relates to an improvement in buckles, and more particularly is for that type of buckle in which the bail or tongue member of the buckle acts as a clamping lever for the free end portion of the strap to which the buckle is applied. More especially, the buckle constitutes an improvement on the buckle shown in Patent No. 1,358,991, dated November 16, 1920, to W. A. Schleicher.

10 In the Schleicher patent there is disclosed a buckle intended to be formed primarily of a malleable casting. The present invention provides a buckle which may be formed of cast metal, but which is particularly intended to be economically manufactured from sheet metal by stamping.

The invention may be readily understood by reference to the accompanying drawings in which

20 Figure 1 represents a plan view of the buckle apart from the strap;

Figure 2 is a side elevation thereof;

25 Figure 3 is a view similar to Fig. 1 showing the manner of attachment of the strap to the buckle; and

Figure 4 is a transverse section on substantially the plane of line IV-IV of Fig. 1.

The buckle comprises a frame member 2 and a bail member 3. The frame member 2 has parallel side bars 4 with downwardly turned flanges 5 in each of which is a hole 6. The side bars 4 are connected at the front of the buckle by the serrated bar 7 and at the back of the buckle by the back bar 8. They are also connected by a top bar 9 which is in a plane above the back bar, as clearly shown in Fig. 4.

30 By reference to Figure 4, it will be seen that the top bar 9 has a convex undersurface 9^a, while the back bar 8 has a convex upper surface 8^a. The serrated bar 7 is preferably flat. The whole frame member 2 as described is formed from a single piece of sheet metal. The bail member 3 is also formed from a single piece of sheet metal.

45 The bail member 3 has a bail bar 10, side bars 11, and a front end bar 12 which is turned upwardly to provide a lip which cooperates with the serrated bar 7. In forming the bail a part of the metal from which the

bail is formed, lying between the side bars 11, is turned back over the main portion of the bail bar providing a rounded surface at 10^a and providing a double thickness of metal for reinforcing the bail bar. The bail bar 55 has reduced end portions 10^b passing through the opening 6 and providing trunnions or a pivotal support for the bail member.

By forming the bail bar as herein described, the bail bar is not only reinforced to a very 60 considerable extent, but the rounded surface 10^a prevents any cutting of the loop of the strap passing around it. This is indicated in Fig. 4 wherein the strap 13 passes around the bail bar, forming a loop 14 which is 65 stitched across at 15. Were the bail member to be formed of sheet metal and the metal not folded back, a sharp edge would be presented to the loop which would eventually cut the strap. Moreover, the width of the 70 bail bar can be reduced because of the greater strength provided by the double thickness of metal.

75 By convexing the top bar 9 transversely, the sheet metal bar is greatly strengthened and at the same time the end of the strap engaged by the buckle, after being pulled up between the front bar 12 of the bail and the serrated bar 7, can be pushed under the top bar very easily, the rounded surface tending to readily guide the end of the strap under the top bar. Likewise, the rounded top of the back bar reinforces the buckle and at the same time keeps the edges of the bar substantially 80 out of contact with the strap so that the edges 85 of the cross bar will not cut into the strap.

The construction of the bail, and the construction of the body of the buckle both permit the buckle to be formed economically of sheet metal and yet provide a buckle which 90 is strong and which will not cut the strap.

I claim:

1. In a buckle, a frame, a bail member pivotally supported in the frame formed of sheet metal and having a bail bar, side bars and a 95 front bar, the metal of the bail bar being rolled over upon itself to reinforce the same and provide a rounded surface for engagement with the loop of a strap when the strap is secured thereto. 100

2. In a buckle, a frame member formed from a single piece of sheet metal having side bar portions with downwardly turned flanges, each of said flanges having a hole therein, a front bar connecting the side portions, a back bar connecting the side portions, the back bar being in a plane below the front bar, a top bar connecting the side portions and being in a plane above the front bar, said top bar being transversely convexed, and a bail member formed from a single piece of sheet metal comprising a bail bar having extensions engaging in the holes in the said side flanges of the frame and having a thickness of metal folded back upon itself to reinforce the same and provide a rounded strap engaging surface.

In testimony whereof I have hereunto set my hand.

CHARLES F. REYNOLDS.
